[57] CLAIM

The ornamental design for a combined cooking plate, drip pan tray and support stand, as shown and described.

DESCRIPTION

FIG. 1 is a perspective view of a combined cooking plate, drip pan tray and support stand showing my design;

FIG. 2 is an exploded perspective view thereof;

FIG. 3 is a top plan view thereof;

FIG. 4 is a bottom plan view thereof;

FIG. 5 is a right side elevational view thereof, the side opposite being a mirror image thereof; and

FIG. 6 is a front elevational view thereof, the rear elevational view being substantially similar.
